By *H. H. Williamson*
Atty.

UNITED STATES PATENT OFFICE.

JOHN A. FRETZ, OF PHILADELPHIA, PENNSYLVANIA.

ATTACHMENT PLUG.

Application filed April 20, 1928. Serial No. 271,452.

My invention relates to a new and useful improvement in an attachment plug such as are designed particularly for use with electrical conductor cords or wires for connecting the conductor cord with an outlet socket or the like whereby electric current may be supplied to an electric appliance such as lamps, fans and irons, and one of the principal objects of this invention is to provide for placing the plug in a screw socket after twisting the electrical conductor cord.

Another object of the invention is to provide an attachment plug consisting of a core which includes a base and stem, contact members carried by said core, a barrel revolvably mounted on the core and including a threaded head, a portion of which coacts with one of the contact members and a screw having threaded engagement with the core and contact with the other of the contact members but insulated from the threaded head of the barrel, said screw holding the barrel in place.

A further object of the invention is to provide unique connections between the poles of the attachment plug and the wires of the electrical conductor cord leading therefrom.

A still further object of my invention is to provide a device of this character which is adaptable to different types of attachment plugs such as separable and inseparable ones.

With these ends in view, this invention consists in the details of construction and combination of elements hereinafter set forth and then specifically designated by the claims.

In order that those skilled in the art to which this invention appertains may understand how to use and make the same, I will describe its construction in detail, referring by numerals to the accompanying drawings forming a part of this application, in which:

Fig. 1, is an upper or outer end view of an attachment plug constructed in accordance with my invention.

Fig. 2, is a side elevation thereof.

Fig. 3, is a longitudinal sectional view on the line 3—3 of Fig. 4.

Fig. 4, is a section on the line 4—4 of Fig. 3.

Fig. 5, is a section on the line 5—5 of Fig. 3.

Fig. 6, is a perspective view of one of the contact members.

Fig. 7, is a side elevation partly in section of a modified form of the device.

Fig. 8, is an upper or outer end view of the core used in connection with either of the forms.

In carrying out my invention as herein embodied, particular reference being had to Figs. 1 to 6 inclusive and 8, the numeral 10 represents the core as a whole including a base 11 and a stem 12, the latter being of smaller cross sectional area than the base to provide a shoulder 13 for a purpose to be later described.

The stem of the core has two curved surfaces 14 separated by two longitudinal channels 15 and through the base of the core are two holes 16 in endwise alignment with the channels 15 and practically form extensions thereof. The upper end of the shank is reduced in size to form a neck 17 which may be of the same diameter as the distance between the two channels which are directly opposite each other.

Within one of the channels is mounted a contact strip or member 18 of suitable electrical conducting metal having a certain amount of resiliency to insure contact with certain elements to be later described and on the upper or outer end of said strip is formed a curved collar 19, the ends of which are separated sufficiently to permit of flexing or moving without binding and this collar partly surrounds the neck 17.

The inner or lower end of the contact strip or member projects into the hole 16 in the core base which is in alignment with the channel in which said strip is mounted and the inner terminal of said strip is bent back upon itself to form a tongue 20 which will engage one of the walls of the hole and tend to force the lower end of the contact strip toward the opposite wall or toward the center of the core, thus providing the desired tension to hold the strip in contact with the usual terminals (not shown) of the ordinary separable member 21 of attachment plugs or the like. This contact strip is held in place by a suitable fastening device 22 such as a screw located intermediate its ends and at some point below such fastening device, the inner end of the strip is bent outward or away from the wall to which the strip is fastened.

A second contact strip or member 23 also of resilient material is mounted in the other

channel with the inner end projecting into the other hole 16 in the core base and said strip 23 is held in place by a suitable fastening device 24 such as a screw.

5 Like the other contact strip 18, the lower end of the contact strip 23 is bent away from the wall to which it is fastened and also has its inner or lower terminal bent back upon itself to provide a tongue 25 which engages a 10 wall of the hole in which it is mounted and therefore tends to force the lower end of said strip toward the center of the core, but the upper end of said strip 23 is bent at substantially right angles to the body thereof to 15 form a lip 26 which projects into a transverse aperture 27 into the shank of the core adjacent the upper or outer end of the latter.

On the stem of the core is revolvably mounted a barrel 28 having an internal diameter equal to that across the core shank between the two curved surfaces 14 and with the inner or lower end of said barrel resting on the shoulder 13 of the core base.

20 The upper end of the barrel carries a screw threaded metal head 29 fixed to said barrel by a suitable fastening device 30 such as a screw, pin or the like and in addition to the screw threaded part, said head includes an 25 end wall 30' from the center of which extends an inwardly projecting circular flange 31 of the proper diameter to enclose the collar 19 of the contact strip 18 and hold said collar under tension in order to insure a positive 30 contact between said flange and collar, thus 35 providing through the head 29 its flange 31, the collar 19 and the body of the contact strip 18 a connection with one side of an electric circuit.

40 About the neck 17 of the core is mounted an insulating washer 32 which rests upon the end wall 30' of the head 29 and said washer is held in place by a suitable cap screw 33 which therefore holds the barrel and its component parts in place while permitting the rotation thereof and the body of said screw is 45 screwed into the threaded hole 34 communicating with the aperture 27 so that when said screw is properly in place, its inner end engages the lip 26 of the contact strip 23, thus 50 providing for connection with the other side of the electrical circuit.

55 In Fig. 7, I have shown identically the same principle utilized in the above described construction with the exception that the contact members 18' and 23' terminate short of the lower or inner end of the core and the fastening devices 22' and 24' are utilized as binding screws so that the conductors or wires of an electrical cord are inserted through the 60 holes 16 of the core base and fastened in place by the screws 22' and 24' instead of the wires being connected with the separable member 21 as in the case of the previously described form. The rest of the parts being similar, I 65 have used the same numbers to designate the

balance of the parts of the attachment plug illustrated in Fig. 7.

In practice, when it is desired to connect the attachment plug with a socket or similar outlet, said attachment plug is inserted in 70 the socket and the barrel 28 revolved so that the screw threaded head 29 will screw into the socket and since said barrel revolves independent of the core, the electrical conductor cord or wires will not be twisted during the 75 operation.

It might be well to mention at this time that the core and barrel are of suitable insulating material to eliminate the possibility of a short 80 circuit.

85 Of course I do not wish to be limited to the exact details of construction as herein shown as these may be varied within the limits of the appended claims without departing from the spirit of my invention.

Having thus fully described my invention, what I claim as new and useful is:

1. An attachment plug including a core consisting of a base having holes therethrough, a shank projecting from the base and including two curved surfaces separated by a pair of oppositely disposed channels, the latter being in endwise alignment with the holes in the base, and a neck at the outer end of the shank, a contact member in one of the channels and having a collar capable of flexion partially surrounding the core neck, another contact member mounted in the other channel and provided with a lip projecting into a transverse aperture in the core shank, a barrel 90 rotatably mounted on the core and engaging the curved surfaces for bearings, a screw threaded head of electrical conductivity mounted on one end of the barrel and provided with an inwardly projecting circular flange 95 for coaction with the collar of the first-mentioned contact strip, an insulating washer surmounting the head, and a screw having threaded engagement with the outer end of the core shank and projecting into engagement with the other contact strip and coacting with the washer to hold it and the barrel with the head thereon in place.

2. In an attachment plug, a core including a base, a shank of smaller diameter than said base, said shank having a pair of oppositely disposed longitudinal channels aligning with holes through the base and further provided with a transverse aperture communicating with one of the channels and a longitudinal hole in the outer end communicating with the aperture, a contact member mounted in one of the channels and having a portion projecting into the aperture, another contact member mounted in the other channel and having a portion disposed adjacent the outer end of said shank, a barrel surrounding the shank, a head carried by said barrel and provided with means for contact with that portion of the second-named contact strip adjacent the 130

outer end of the core shank, and means insulated from the head and mounted in the hole in the outer end of the core shank to engage that portion of the first-mentioned contact strip which projects into the transverse aperture and to hold the barrel on the core while permitting it to revolve.

3. The structure set forth in claim 2 where-
in the inner ends of the contact strips project

into the holes in the core base and have their 10 terminals bent back upon themselves for engagement with walls of said holes to provide spring action at the inner ends of said contact strips.

In testimony whereof, I have hereunto af- 15 fixed my signature.

JOHN A. FRETZ.
